METAL-BENDING MACHINE.

1,122,092.

Specification of Letters Patent. Patented Dec. 22, 1914.

Application filed March 30, 1912. Serial No. 687,306.

To all whom it may concern:

Be it known that I, JOHN M. FEDDERS, a citizen of the United States, residing at Buffalo, in the county of Erie and State of New York, have invented new and useful Improvements in Metal-Bending Machines, of which the following is a specification.

This invention relates to a metal bending machine which is more particularly designed for bending a strip of sheet metal so as to form a succession of laterally projecting plaits and also longitudinal offsets thereon for use in the manufacture of water cooling radiators for automobiles.

It is the object of this invention to produce a machine of this character which will permit of producing such strips expeditiously and economically and without stretching the metal while forming the plaits, and in which the various parts are so organized that the same are not liable to get out of order and the wear upon the same is reduced to a minimum.

In the accompanying drawings consisting of 2 sheets: Figure 1 is a fragmentary vertical longitudinal section of a press or bending machine embodying my invention, the parts being represented in a position in which the punch and die are separated to their fullest extent. Fig. 2 is a similar view of the same but showing the parts in an intermediate position. Fig. 3 is a vertical transverse section taken substantially in line 3—3, Fig. 1. Fig. 4 is a bottom plan view of the punch. Fig. 5 is a top plan view of the die. Fig. 6 is a fragmentary vertical longitudinal section taken in line 6—6, Fig. 5. Fig. 7 is a fragmentary perspective view of the plated radiator strip which is produced by my improved bending machine.

Similar characters of reference indicate corresponding parts throughout the several views.

The radiator strip produced by my improved bending machine is made of sheet metal and in its finished condition comprises a succession of transverse webs 1 which are arranged lengthwise side by side 50 and in line with each other so as to form a longitudinal row, a plurality of laterally projecting plaits 2 the walls of which are connected at their outer edges while their inner edges are connected respectively with 55 the opposing transverse edges of two adja-

cent webs, and outwardly projecting offsets or beads 3 arranged longitudinally at opposite lateral edges of the webs, the offsets at corresponding lateral edges of the webs being arranged in line in a direction lengthwise of the strip.

Taken in its entirety 4 represents the die or lower member of the bending machine and 5 the punch or upper member thereof which is movable vertically toward and 65 from the die. The die is mounted on a stationary holder, support or table 6 while the punch is mounted on a vertically movable head or holder 7 which may be operated by any suitable or well known means, such 70 operating mechanism not being shown in the drawings inasmuch as the same may be like that now in general use.

In its general organization the die comprises a body or base having front and rear 75 cross bars 8, 9 and two longitudinal side bars 10 connecting corresponding ends of the front and rear bars so that the same in effect forms a rectangular open frame resting upon the upper side of the support or table. 80 Within the frame-shaped die base or body are arranged the die members or sections proper, the same comprising a front die section 11, an intermediate die section 12 and a rear die section 13. The front die section 85 is arranged within the front part of the base and secured to the front cross bar by screws 14 or otherwise so as to be fixed or held stationary and the same is provided on its upper side with a flat horizontal face 15 90 and two longitudinal ribs, beads or raised portions 16 arranged at opposite ends of the upper flat portions of this section. The upright rear transverse side of this front guide section has a lower vertical portion 17 95 while the corner between the upper end of this rear side and the rear end of the upper side of this die section is rounded or beveled slightly, as shown at 18 in Figs. 1 and 2.

The intermediate die section is provided 100 on its front side with an upright face 19 which co-operates with the vertical face of the front die section, on its rear side with a vertical transverse lower face 20 and on its upper side with a horizontal face 21 and 105 longitudinal upwardly projecting ribs or raised portions 22. The upper front corner of the intermediate die section is beveled, as shown at 23. Normally this intermediate die section is yieldingly held in an elevated 110

position so that the upper side thereof is arranged above the upper side of the front die section a distance substantially equal to the depth of the plaits of the radiator strip and the underside of this die section is raised above the table or support of the die to a similar extent, as shown in full lines in Fig. 1. The intermediate die section is moved vertically and the same is guided in this movement preferably by engagement of its front side with the rear side of the front section and by engagement of its opposite ends with the inner sides of the side bars and also by means of vertical guide rods 21 each of which is secured at its upper end to the underside of the intermediate die section while its lower end slides in a vertical guideway 25 formed in the adjacent part of the support 6. The upward movement of this guide section is limited by means of enlargements or heads 26 formed at the lower ends of the guide rods 24 and adapted to engage with downwardly facing shoulders 27 formed in said guideways, as shown in Fig. 3.

The rear section of the die is arranged in rear of the intermediate section and is capable of both a vertically and also a horizontally reciprocating movement. On its front side the rear die section is provided with a lower vertical transverse face 28 which is arranged opposite the vertical rear face of the intermediate section, a horizontal upper face 29, upwardly projecting longitudinal ribs or raised portions 30 arranged at opposite ends of the upper horizontal face, and a downwardly recessed rabbet 31 of rectangular form arranged in rear of the upper horizontal face. The rear die section is guided in its horizontal and vertical movements preferably by means of two upright guide rods 32 each of which is secured at its upper end to the underside of this section while its lower end slides in a guideway 33 formed in the adjacent part of the support or table, these guideways being elongated lengthwise of the die so as to permit of the requisite longitudinal movement of this section. The upward movement of the rear die section is limited by means of an enlargement or head 34 formed at the lower end of each of the guide rods 32 and engaging with a downwardly facing shoulder 35 formed in the guideway 33, as shown in Fig. 6.

Various means may be employed for yieldingly holding the intermediate and rear guide sections in an elevated position but those shown in the drawings are preferred and comprise a plurality of vertical movable lifting rods 36 guided in suitable ways 37 formed in the support or table and engaging loosely at their upper ends with the undersides of the intermediate and rear die sections, a lifting disk or plate 38 arranged

below the table or support and engaging with the lower ends of the lifting rods, a main supporting rod 39 depending from the underside of the table and serving as a guide for the lifting disk, and a spring 40 surrounding the main supporting rod and bearing at its upper end against the underside of the lifting disk while its lower end rests upon a washer 41 which engages with a head 42 at the lower end of the main supporting rod, as shown in Figs. 1, 2 and 3. The upward movement of the lifting plate is preferably limited by engagement with the underside of the table. In the elevated position of the rear guide section its upper and lower sides are flush with the corresponding sides of the intermediate die sections. The elevated ribs of the several die sections at the corresponding ends thereof are arranged lengthwise in line, as shown in Fig. 5.

The longitudinal horizontal movement of the rear die section may be produced by various means, the means for this purpose shown in the drawings consisting of springs 43 interposed between the lower opposing vertical faces of the intermediate and rear die sections and each seated at its opposite ends in suitable pockets formed in these die sections so as to prevent displacement thereof, and an inclined face 44 formed on the lower rear side of the rear die section and engaging with an inclined face 45 formed on the front side of a stationary abutment block 46 arranged upon the table within the rear part of the die base and secured by bolts 47 or otherwise to the rear bar of the base, as shown in Figs. 1 and 2. Upon depressing the rear die section the same is moved horizontally forward by the wedge or cam action of its rear inclined face with the inclined face at the front end of the abutment block, and when the rear die section is elevated the same is moved horizontally rearward by the resilience of the springs 43. Projecting upwardly from the bottom of the rabbet on the rear die section are two retaining pins or lugs 48 which have their upper ends flush with the upper sides of this die section and are separated from the vertical front wall of the rabbet by an intervening space or gap.

Means are provided for holding the sheet metal blank from which the radiator section is constructed in an elevated position above the faces of the intermediate and rear die sections while the die and punch are separated or open which means also serve to lift this radiator section from the die after the bending operation has been completed so as to permit the blank to be moved forwardly step by step after the successive bending operations have been performed on the same. This lifting device preferably comprises two vertically movable ejector or lifting rods 49 which are guided in suit-

able openings or ways 50 formed in the front die section, and springs 80 arranged in pockets 51 formed in the table and engaging with the lower ends of these ejecting pins. In their elevated position the upper ends of these ejecting pins are arranged above the upper face of the front die section a distance equal to twice the height of the plaits of the finished radiator strip and the extent of this movement is limited preferably by means of enlargements or stop heads 52 formed at the lower ends of the ejecting pins and engaging with the under side of the front die section.

15 Although the punch so far as its detail construction is concerned may be varied to some extent it is preferably constructed as follows: 53 represents the body or base of the punch which may be secured to the vertically movable head or holder by means of screws 54, as shown, or any other suitable means. On its underside the punch body or base is provided near its front end with a transverse punch blade, former or tongue 55 which is adapted to coöperate with the rear side of the front die section and the beveled front corner of the intermediate die section for effecting a preliminary or partial bending of the metal of the blank for partly bending one of the plaits thereon. This punch blade is preferably removably secured to the punch base by arranging the upper part of this blade in a slot or groove 56 in said base and securing the same therein by means of set screws 57 so that this blade projects below the face of the punch base an extent equal to the height of one of the plaits of the radiator strip. The front side 58 of the front blade is vertical and in line with the rear side of the front die section and the rear side 59 of the same is beveled and arranged parallel with the inclined face at the upper front corner of the intermediate die section. In rear of the punch blade is arranged a clamping block or jaw 60 which is movable vertically relatively to the punch base and which is adapted to press the radiator blank against the upper sides or faces of the intermediate and rear guide sections 50 during the operation of forming the plaits and offsets thereon. This clamping block is movable vertically in a recess 61 formed in the underside of the punch body in rear of the punch blade and is provided with a flat horizontal face 62 on its underside which is adapted to coöperate with the flat upper beads of the intermediate and rear die sections and with longitudinal grooves 63 near opposite ends of its flat face which are adapted to receive the longitudinal ribs or beads of the intermediate and rear die sections. The clamping block may be guided in its vertical movements relatively to the punch base by any suitable means but preferably by the means which are shown in the drawings and which comprise two upright guide screws or rods 64 secured at their lower ends to the underside of the clamping block while their upper ends are arranged in vertical guideways 65 formed partly in the punch body and the base, as shown in Figs. 1, 2 and 3. In its lowermost position relatively to the punch body and blade the clamping block has its lower face arranged below the lower edge of said blade, as shown in Fig. 1. The clamping block is yieldingly held in this position by means of vertically movable pressure rods 66 secured at their lower ends to the upper side of the clamping block and guided at their upper ends in ways 67 formed partly in the punch body and partly in the punch holder, and springs 68 each of which is arranged in the upper ends of one of said guideways 67 and bears against the upper end of the respective presser rod. The downward movement of the clamping block relatively to the punch body and blade is limited by means of a stop device which preferably consists of enlargements or heads 69 formed at the upper ends of the guide rods 64 and presser rods 66 and adapted to engage with upwardly facing shoulders 70 formed in their companion guideways. Those portions of the underside of the punch body in front and in rear of the punch blade are provided with horizontal bearing faces 71, 72 which are adapted to coöperate with the corresponding flat upper faces of the front and intermediate die sections, and near opposite ends of these flat faces the punch body is provided with longitudinal grooves 73, 74 which are arranged lengthwise in line with the companion grooves of the clamping block and are adapted to coöperate with the ribs or beads of the front and intermediate die sections for forming offsets at opposite edges of the radiator strip. The sheet of metal from which the radiator strip is constructed may be supplied to the machine and fed forward intermittently one step at a time with an interval of rest between each step by any suitable means.

40 In Fig. 1 the parts are represented in full lines in the position which they assume when the die and punch are fully separated and the sheet metal blank has been fed forward one step preparatory to being operated upon for producing the next plait and offset forming operation thereon. It will be noted that in this position of the parts the intermediate and rear sections of the die are in their uppermost position, the blank is lifted by the ejecting pins into a position in which the completed and partly completed plaits are arranged wholly above the upper faces of the intermediate and front die sections, and the clamping block of the punch is depressed and has its lower face arranged below the lower edge of the punch blade.

45 50 55 60 65 70 75 80 85 90 95 100 105 110 115 120 125 130

During the first step of the downward movement of the punch the underside of the clamping block is brought into engagement with the blank above the intermediate and rear die sections whereby the adjacent part of the blank is clamped between this block and these die sections but the punch blade is still out of engagement from the blank, as shown by dotted lines in Fig. 1. During the next following step of the downward movement of the punch the clamping block and intermediate and rear die sections remain at rest while the body of the punch and the punch blade move downwardly independently of said clamping block and intermediate and rear die sections, thereby causing the underside of the punch body in rear of the punch blade to bear upon the blank resting upon the adjacent part of the intermediate die section and also causing the beveled face of the punch blade to bend the adjacent part of the blank downwardly into engagement with the beveled upper front corner of the intermediate die section, as shown by full lines at 75 in Fig. 2 and form the rear wall of a plait. The intermediate and rear die sections are thus held in their uppermost and elevated position while the clamping block recedes into its recess in the punch body by reason of the spring 40 which sustains the intermediate and rear die sections being stiffer or stronger than the springs 68 which tend to depress the clamping block. While the punch blade is thus bending the metal blank the ejector pins also recede downwardly into the front die section so that that part of the blank immediately in front of the punch blade or former will rest upon the upper side of the front die section, as represented by full lines in Fig. 2. During the next following and final downward step of the die and associated parts the body, blade and block of the punch as well as the intermediate and rear die sections of the die move in unison from the position shown by full lines in Fig. 2 to the position shown by dotted lines in this same figure, thereby causing the punch blade to move downwardly along the rear side of the front die section, whereby the metal of the blank in front of the blade is moved forwardly and downwardly along the rear side of the front die section at right angles to the body of the blank a sufficient extent to form the front wall 76 of the plaits which vertical wall is a companion to the inclined rear wall 75 of the plait formed between the beveled faces of the die blade and intermediate die section.

While the intermediate and rear die sections are in their elevated and separated position the first part of the downward movement of the punch causes its clamping block to press the sheet metal blank so that the previously partially formed plait having

the vertical front wall and the inclined rear wall enters between the upper parts of the intermediate and rear guide sections, as represented by full lines in Fig. 2. As the clamping block and the intermediate and rear sections of the die move downwardly in unison during the final step of the bending operation, the rear die section is moved forwardly toward the intermediate die section, thereby causing the folding of the plait of the radiator strip between the intermediate and rear die sections to be completed. As the blank is pressed downwardly by the punch against the die each completed blank enters the rabbet formed on the rear part of the rear die section so that the same is not affected by the formation of the succeeding plaits and that part of the radiator strip immediately in rear of the first completed plait is supported by the retaining pins 48 so as to prevent distortion of the strip during the operation of forming succeeding plaits thereon.

While the members of the punch and die are coöperating with each other in the manner described for producing a partial plait on one portion of the blank and completing another plait on another part of the blank the coöperating longitudinal ribs and grooves of the die and punch members produce the longitudinal offsets at opposite longitudinal edges of the webs of the radiator strip. These offsets are partially formed by the ribs of the front die section and the grooves of the punch body in front of the punch blade and these offsets are completed subsequently by coöperation of the ribs on the intermediate die sections with the offset grooves in the punch body in rear of the blade and the front part of the offset grooves in the clamping block and by engagement of the offset ribs of the rear die section with the rear part of the offset grooves in the clamping block. After the punch has completed its downward stroke relatively to the die and has effected the partial formation of one plait and completed the formation of another plait the punch is raised to its highest position. During the first part of this movement the punch body, blade and block and also the intermediate and rear die sections move upwardly together. When the intermediate and rear die sections have reached their uppermost position the punch body and blade continue their upward movement while the punch block remains in engagement with the intermediate and rear die sections and during the last part of the upward movement of the punch the clamping block is lifted from the intermediate and rear die sections and the ejector pins raise the strip blank so that its plaits are above the upper surfaces of the last mentioned die sections. At the same time that the in-

termediate and rear die sections are raised the completed bead of the radiator section is released by reason of the rearward movement of the rear die section under the action of the springs 43.

By inserting shims 77 of varying thicknesses between the abutment block and the rear cross bar of the die holder it is possible to adjust the horizontal throw of the rear die section for admitting the same to fold the plaits more or less closely as desired and also for taking up wear on the coöperating inclined surfaces of these parts. The front and rear working faces of the intermediate die section and the front working face of the rear die section are each preferably cut back slightly in the central parts of the same while the end parts are left full, as shown in Figs. 1, 2, 3 and 5. By this means the ends of the walls of each plait are pressed firmly together for presenting a solid or continuous edge on the front and rear sides of the finished radiator while the parts of each plait intermediate 25 of its ends are separated so as to permit water to enter into these spaces and thereby increase the cooling efficiency of the radiator.

My improved construction of bending machine for producing these plaited and offset radiator sections or strips is so organized that the metal at no time is stretched or distorted but is merely bent naturally, thereby preventing variation in the length of the strips or in the spacing of the distances between adjacent plaits, whereby the assembling of the strips in the manufacture of the radiators is facilitated and uniform and better fitting radiator tubes are insured. Moreover by avoiding stretching of the metal it is immaterial whether or not the same is tempered and all liability of weakening the metal or forming leak holes in the same is avoided. Furthermore, in my improved construction of bending machine the metal is operated upon in such manner as to result in a minimum strain or wear upon the dies, thereby

reducing the liability of getting them out of order as well as effecting a saving in the cost of repairs.

I claim as my invention:

1. A metal bending machine comprising a die having a fixed front section, a vertically movable intermediate section coöperating with said front section, and a vertically and horizontally movable rear section coöperating with the intermediate section and a vertically movable punch having a body coöperating with the upper sides of said front and intermediate die sections, a blade fixed on the body and adapted to coöperate with the rear side of said front die section and the upper front corner of said intermediate die section, and a clamping block movable vertically independently of said blade and body and adapted to coöperate with the upper sides of said intermediate and rear die sections.

2. A metal bending machine comprising a die having a fixed front section, a vertically movable intermediate section coöperating with said front section, and a vertically and horizontally movable rear section coöperating with the intermediate section, a vertically movable punch having a body coöperating with the upper sides of said front and intermediate die sections, a blade fixed on the body and adapted to coöperate with the rear side of said front die section and the upper front corner of said intermediate die section, and a clamping block movable vertically independently of said blade and body and adapted to coöperate with the upper sides of said intermediate and rear die sections, means for holding said intermediate and rear die sections yieldingly in an elevated position, and means for holding said clamping block yieldingly in a depressed position.

Witness my hand this 28th day of March, 1912.

JOHN M. FEDDERS.

Witnesses:

THEO. L. POPP,
E. M. GRAHAM.

It is hereby certified that in Letters Patent No. 1,122,092, granted December 22, 1914, upon the application of John M. Fedders, of Buffalo, New York, for an improvement in "Metal-Bending Machines," errors appear in the printed specification requiring correction as follows: Page 3, line 57, strike out the words "beads of the intermediate and rear" and insert the words *faces of the upper and intermediate*; page 5, line 10, for the word "admitting" read *adapted*; and that the said Letters Patent should be read with these corrections therein that the same may conform to the record of the case in the Patent Office.

Signed and sealed this 19th day of January, A. D., 1915.

[SEAL.]

R. F. WHITEHEAD,

Acting Commissioner of Patents.
